UNITED STATES PATENT OFFICE.

CHARLES E. ZIEGLER, OF ALTWASSER, GERMANY, ASSIGNOR TO THE J. POUYAT COMPANY, OF NEW YORK, N. Y.

DESIGN FOR A COVERED DISH OR SIMILAR ARTICLE.

43,130.

Specification for Design.

Patented Oct. 8, 1912.

Application filed January 10, 1912. Serial No. 670,504. Term of patent 3½ years.

To all whom it may concern:

Be it known that I, CHARLES E. ZIEGLER, a citizen of the Republic of France, residing at Altwasser, Silesia, Germany, have invented a new, original, and ornamental Design for a Covered Dish or Similar Article, of which the following is a specification, reference being had to the accompanying drawings, forming part thereof.

Figure 1 is a side elevation of a covered dish or similar article showing my design; and Fig. 2 is a plan view of the same.

I claim:

The ornamental design for a covered dish or similar article as shown.

CHARLES E. ZIEGLER.

Witnesses:

HENRY HASPER,
WOLDEMAR HAUPT.
